CASKET SEAL

William L. Slaughter, Cincinnati, Ohio, assignor to The Crane & Breed Casket Company, Cincinnati, Ohio, a corporation of Ohio

Filed Sept. 3, 1964, Ser. No. 394,297
2 Claims. (Cl. 49—485)

The present invention relates to a casket seal, such as is applicable particularly to burial caskets.

In the use of burial caskets, the sealing of the casket must usually be performed within a limited space of time, and without much attention devoted to the mechanics of effecting a satisfactory seal incident to closing the lid upon the casket body. It is therefore the responsibility of the casket manufacturer to provide sealing means of a highly reliable type, which can be expected to effect a seal with precision upon mere closing of the lid in casual manner.

An object of the present invention is to provide in a burial casket construction, a highly reliable sealing means which can be depended upon to invariably tightly seal the casket upon casual closing of the lid upon the casket rim.

Another object of the invention is to provide sealing means of the character stated, which furnishes effective multiple barriers to movement of air and water past the seal.

Another object is to provide an improved sealing means having the advantages above noted, which is highly durable, and simple and inexpensive to manufacture and apply to a burial casket.

The foregoing and other objects are attained by the means described herein, and illustrated upon the accompanying drawing, in which:

FIG. 1 is a fragmental perspective view of the improved sealing means for a burial casket.

FIG. 2 is an enlarged transverse cross-section taken through a burial casket rim and lid, the lid being out of contact with the sealing means.

FIG. 3 is a view similar to FIG. 2, with the lid closed upon the sealing means.

FIG. 4 is a fragmentary top plan view of the sealing means of the invention, showing a corner construction thereof.

In the drawing, the numeral 10 denotes the upper rim portion of a burial casket 12, and 14 indicates a lid for the casket. The lid usually is hinged upon the casket body, and may be swung from an open to a closed position relative to the casket rim. The lid has a peripheral planar sealing area 16 which, in the closed position of the lid, overlies an upper peripheral jamb face 18 of the casket rim. Face 18 is adapted to support a gasket or sealing strip 20, which may be cemented, screwed, or otherwise secured thereon. Lid area 16 seals against gasket 20 when closed upon the casket body, to provide a multiple seal.

The gasket or sealing strip may be of flexible rubber-like plastic material, such as neoprene, molded substantially in rectangular form (FIG. 1), and having a planar back or lower face 22 to overlie the casket rim area 16. The gasket width is defined by outer and inner edges 24 and 26, respectively, which may be parallel to one another, and which meet at the gasket ends to form corners 28 fitting the corners of rim 10.

The upper or exposed face 30 of gasket 20 carries a pair of pressure-deformable lips 32, 34, based upon face 30, and projected away from said face at an angle inclined from the vertical, so that the lips gradually converge at a location remote from face 30, to provide a narrow gap 36. The free edges 38 of the lips define the width of gap 36, and are parallel to one another all

2

around the extent of the gasket. The lips are soft and resilient, and may taper gradually thin in the direction of the free edges 38.

From the foregoing, it will be apparent that lowering 5 of lid 14 to the FIG. 3 position, results in turning the lips inwardly toward one another to partially flatten the lips and reduce the gap 36. To obtain the most effective double seal between lips 32, 34, and the sealing area 16 of the lid, the lips should be so proportioned that the 10 free edges 38 thereof approach one another without actually meeting, when the lid descends to its maximal closing position. Thus, a pair of spaced parallel seals are produced, with an air space or channel between them, along the full perimeter of lid sealing area 16. It will be 15 noted by referring to FIG. 3, that lips 32 and 34 in the fully closed position of lid 14, bend inwardly at a location above upper face 30 of the gasket, and do not flatten against said face 30 intermediate the lips; nor do the free edges of the lips meet at gap 36. The confining 20 air space beneath gap 36 is an important feature of the invention, along with the independent parallel seals formed by the lips against the lid face 16.

If desired, the upper face of gasket 20 may be provided 25 with one or more upstanding ribs 40 arranged in parallelism with lips 32, 34; such ribs being preferably at a lower elevation than the lips with relation to gasket face 30, so that said ribs 40 may provide additional seals against lid face 16 while at the same time limiting the extent to 30 which said lid face 16 compresses and deforms the lips 32 and 34 when the lid is fully closed. Ribs 40, being upwardly extended only a limited distance, are more resistive to compression than lips 32 and 34 and will therefore effectively limit the lowering movement of the casket lid while at the same time producing a seal therewith. 35 Ribs 40, like the lips 32 and 34, are inherently flexible and resilient.

The numeral 42 denotes a shrine for the casket, suitably attached to the body rim interiorly thereof, for example as disclosed in my copending application Ser. No. 40 156,648, filed Dec. 4, 1961. A retainer for the shrine may comprise a down-turned flange 44 on the rim 10, and a U-shaped channel member 46 cooperating with the flange to form a socket in which is retained the tongue 48 of the shrine. The channel member 46 may include a base 45 50 welded or otherwise secured to the rim. The shrine and its mounting form no part of the present invention, and need not therefore be disclosed in greater detail.

From the foregoing disclosure and explanation, it should be evident that lowering of the casket lid must necessarily 50 result in turning the gasket lips 32 and 34 inwardly toward one another to form the intended seals. The inwardly arched predisposition of the lips precludes the possibility that one lip, or a portion of a lip, might be turned in a contrary direction by the lid in closing. Moreover, the 55 shrine or any other object which might overlie the sealing lips during an extended period of time, will have no tendency to deform the lips in any direction other than that which is favorable to proper subsequent sealing against the casket lid. Thus, the entire arrangement is 60 such that mere casual closing of the lid will ensure effective sealing as intended.

It is to be understood that various modifications and changes may be made in the structural details of the device, within the scope of the appended claims, without departing from the spirit of the invention.

What is claimed is:

1. A gasket for effecting a seal between the peripheral upper rim of a burial casket, and a peripheral sealing area of a casket lid, said gasket comprising: a strip of flexible 70 resilient rubber-like plastic material having spaced outer and inner edges, and an intervening planar base area to rest upon the casket rim; an upper face on the base area

exposed to the sealing area of the lid rib; a pair of flexible and resilient parallel lips based upon said exposed face and projected upwardly therefrom, said lips having resilient free edges spaced apart and curved toward one another to form a gap therebetween and an underlying air chamber defined by the lips and the upper face of the gasket base; a plurality of continuous parallel resilient ribs upstanding upon the upper face of the gasket base coextensively with the lips aforesaid, to contact and resiliently self-adjust uniformly upon the full perimeter of the sealing area of the lid in closing, said ribs being extended above the upper face of the gasket base a distance such as to limit deflection of the resilient lip edges incident to full closing of the lid thereon, to the extent of reducing the gap between the lips short of actual closing of said gap.

2. The gasket as specified by claim 1, wherein the strip

5 constituting the gasket is formed as a unitary open endless frame dimensioned to overlie and substantially cover the peripheral upper rim of the burial casket.
